UNITED STATES PATENT OFFICE.

ALOYZIUS R. BLASKI, OF CHICAGO, ILLINOIS.

ACTUATING MECHANISM FOR SKYLIGHT SECTIONS AND THE LIKE.

Application filed September 12, 1924. Serial No. 737,383.

My invention relates to skylight structures and the operation of the sections for ventilation purposes.

One of the objects of my invention is the provision of actuating mechanism for skylight sections and similar uses which is very simple in construction, reliable in operation, capable of quick and easy installation and inexpensive to manufacture.

10 Further objects of my invention are to provide a mechanism that will open and close hinged sections on either side of a skylight and the like to any position intermediate of closed to open either on one side 15 or on both sides.

Further objects of my invention are to provide a mechanism that will perform its cycle or cycles of operation by a continual movement in one direction without jamming.

20 To attain these objects I use a continuous chain mounted on several sprockets, and provide a means for moving this chain around these sprockets, and through links connected to the chain and skylight sash, I 25 attain the object of opening the sections at either one or both sides of the skylight. In the drawing,—

Fig. 1 is a front view of the entire mechanism, as it appears in use on a skylight 30 having top hinged sash on either side.

Fig. 2 is a diagram showing various positions of the skylight sash as actuated by the operating mechanism.

35 In Fig. 1, a fragmentary portion of a skylight is shown comprising two top hinged sash 1, adapted to close the opening formed between two lower stationary sash 2. Links 3 and 3^A are hingedly connected at their upper ends to rafters of the sash 1, at 4, and the bottom ends of the links are pivotally connected to the chain 6 at 5. Sprockets 7, 8, 9 and 10 are revolvably mounted on the framework 11 for movably supporting the chain 6. A sprocket 12, keyed to a longitudinally extending shaft 13, meshes with the chain for driving it in either direction, such shaft being driven from any suitable source of power.

40 Referring to Fig. 2, a more detailed explanation is given showing the various positions of the ventilating sash 1—1 resulting from the movement of the mechanism heretofore described. For the sake of clearness

the various positions of the skylight sash and actuating mechanism are shown by lines and designated by letters. Starting from a position when both sides of the skylight are closed the various parts are shown as left sash A, and link B; right hand sash D, and link C, and the juncture of the two links at the bottom as Q. Assuming that the chain 6 is being moved in counter-clockwise direction for a part of its possible travel, the various parts will take the positions as shown by the lines as; left hand sash A, and link E, right hand sash G, and link F, and the juncture of the bottom ends of the links as R. The next movement of the chain 6 can be stopped to result in the positions as; left hand sash A, and link H, right hand sash J and link I and the juncture of the bottom ends of the links as S. It will be noted that in the last noted positions the right hand sash J has reached substantially its uppermost position, and that the left hand sash A has remained practically stationary, the chain 6 yielding slightly downwardly and to the right so as to prevent any substantial movement of the sash at the left. The other positions of the sash as the movement of the chain continues in the same direction are indicated as; right hand sash J, and link K, left hand sash as M and link L, and the juncture of the two links at the chain as T. The next position shows both sash in the maximum open position, as right hand sash J, link N, left hand sash P, and link O, and the juncture of the two links at the chain as U.

45 Upon a continued movement of the chain 6 in counter-clockwise direction, the lower ends of the links 3 and 3^A are moved downwardly and toward the left. Such movement serves to close the sash at the right, while the link at the left merely swings with respect to the sash at that side without materially changing the position of the sash. Upon the further movement of the chain, the lower ends of the links are moved downwardly and toward the right, serving to close the sash at the left while keeping the sash at the right substantially closed.

50 Since the operating mechanism is similar at its opposite sides, it is capable of operating to equal advantage in either direction. As will be readily understood, when the

chain 6 is driven in clockwise direction, the sash or section at the left is opened first, followed by the opening of the sash at the right. Upon continued movement in such 5 clockwise direction, the sash at the left is closed first, followed by the closing of the sash at the right.

It will be understood also that with both 10 sections standing in their fully opened position, they may be closed by movement of the chain 6 in either direction regardless of the direction in which the chain was moved for opening them.

By the use of my improved mechanism, 15 either sash can be opened to precisely the desired extent with the other sash entirely closed or substantially so. In like manner, either sash can be opened to precisely the desired extent with the other sash in its fully 20 opened position. When it is desired to have both sections open at the same time, with both in fully opened position or with one in fully opened position and the other only partially opened, the mechanism can be operated for opening the sash at either side first as may be desired, this depending entirely upon the direction in which the chain 6 is moved for effecting the opening operation.

30 While I prefer to employ a construction substantially as shown in the drawing and as above described, I wish to have it understood that I do not limit the invention to the form shown, except so far as certain of the 35 claims may be specifically so limited, since it is evident that changes might well be made without departing from the spirit of my invention.

I claim:

40 1. A ventilating construction, comprising in combination a supporting structure having an opening therein, a swingingly-mounted section adapted to close said opening, a flexible member in the form of a loop, means for supporting said member in vertically disposed position at spaced points therealong and for moving it about the supports, and a link connected at its lower end with said flexible member and at its upper end 45 with said swingingly-mounted section adapted in one position of the flexible member to support the section directly from the flexible member in partially opened position and in another position of the flexible member to 50 hold the section in closed position.

2. A ventilating construction, comprising in combination a supporting structure having an opening therein, a swingingly-mounted 60 section adapted to close said opening, a flexible member in the form of a loop, means for supporting said flexible member at spaced points therealong and for moving it about the supports, and a link connected with said flexible member and said swingingly-mounted section adapted by substan-

tially half a revolution of the flexible member in one direction to open said section and by the succeeding half revolution in the same direction to close said section.

3. A ventilating construction, comprising 70 in combination a supporting structure having an opening therein, a swingingly-mounted section adapted to close said opening, a flexible member in the form of a loop, 75 means for supporting said flexible member at spaced points therealong and for moving it about the supports, and a link connected with said flexible member and with said swingingly-mounted section adapted by substantially a quarter of a revolution of the flexible member in one direction to open said section, by a succeeding quarter of a revolution to hold the section in substantially unchanged position, by the succeeding quarter of a revolution to move the section to closed position, and by the succeeding quarter of a revolution to maintain the section in closed position.

4. A ventilating construction, comprising 80 in combination a supporting structure having an opening therein, a pair of swingingly-mounted sections adapted to close said opening, a flexible member in the form of a loop, 85 means for supporting said member at spaced points therealong and for moving it about the supports, and links connected with said flexible member and the respective sections adapted in one position of the flexible member to hold both sections closed, in another position to hold one section open and the other closed, in another position to hold both sections closed, and in a fourth position to hold the first-opened section closed and the other section open.

5. A ventilating construction, comprising 90 in combination a supporting structure having an opening therein, a section hingedly mounted at its upper end adapted in diagonal position to close said opening, a flexible member in the form of a loop, a plurality of supporting means revolvably mounted on horizontal axes in spaced relation to each other for supporting said flexible member and for moving it thereabout, and a link 95 connected with said flexible member and with said swingingly mounted section adapted to be moved upwardly by the movement of said flexible member about its supports for raising the section to its opened position.

6. A ventilating construction, comprising 100 in combination a supporting structure having an opening therein, a section hingedly mounted at its upper end adapted in diagonal position to close said opening, a flexible member in the form of a loop, a plurality of supporting means revolvably mounted on horizontal axes in spaced relation to each other for supporting said flexible member and for moving it thereabout, and a link 105 connected with said flexible member and 110

with said swingingly mounted section adapted by a portion of the movement of the flexible member to move the section to its open position, by the next succeeding portion of the movement of the flexible member in the same direction to hold the section in raised position substantially without change, by the

next succeeding portion of the movement in the same direction to close the section, and by the remaining portion of a complete 10 cycle of movement to hold the section substantially closed.
